UNITED STATES PATENT OFFICE.

CLINTON W. HOUGH, OF BOONVILLE, NEW YORK, ASSIGNOR TO WIRED RADIO, INC., OF NEW YORK, N. Y., A CORPORATION OF DELAWARE.

ELECTRON-TUBE SYSTEM.

Application filed January 18, 1926. Serial No. 81,826.

My invention relates broadly to power supply circuits for electron tubes, and more particularly to a method of operating electron tubes from a source of alternating current

5 rent supply without transformation.

One of the objects of my invention is to provide a method of operating electron tubes from an alternating current supply without the necessity of inter-positioning a transformer between the electron tube circuits and the power supply system for supplying both cathode heating current and plate potential for the operation of the electron tube.

Another object of my invention is to provide a construction of electron tube which may be operated from a source of house lighting current without the necessity of employing battery supply systems with all of the inherent disadvantages thereof.

20 Another object of my invention is to provide a construction of electron tube which may be operated from a source of alternating current supply in which the cathode is divided into two portions with a resistance 25 interposed therebetween and sets of grid and plate electrodes provided adjacent the electron emitting portions in such manner that the plate electrodes function when connected with external circuits in cooperation with the cathodes as double wave rectifiers of the 30 A. C. supply which is impressed across the filament for supplying the direct current plate potential for the tube system.

Still another object of my invention is 35 to provide an arrangement of cathode for an electron tube by which a drop substantially equal to the impressed voltage may be obtained across the cathode and alternating current supplied thereto and rectified for 40 supplying the potential for the plate circuit of the electron tube.

Other and further objects of my invention will be understood from the specification hereinafter following by reference to the accompanying drawings, in which:

Figure 1 illustrates diagrammatically the principles of my invention; Fig. 2 shows a plurality of electron tubes constructed in accordance with my invention and connected 50 in a cascade for the amplification of signaling energy; Fig. 3 is an enlarged fragmentary view of one form of cathode construction which may be employed in the electron tube construction of my invention; and

Figs. 4 and 5 are cross-sectional views taken 55 through the cathode construction of Fig. 3; and Fig. 6 shows a modified construction of cathode.

In a radio receiving apparatus in which a multiple number of tubes is employed for 60 amplifying relatively feeble incoming signaling energy, it has been proposed to employ alternating current as a source of power supply in the operation of the tube circuit, but such installations have been relatively complicated and in attempting to employ the usual construction of electron tube for such operation it has not been entirely satisfactory by reason of hum and undesired 65 noises produced in the sensitive amplification system by virtue of the existence of disturbing currents in the amplification system arising from the source of low frequency power supply. In such apparatus it is also necessary to provide transformer equipment and 70 independent rectifier tubes for securing the plate potential. By my invention I provide a construction of electron tube which may be operated from the usual source of residence lighting current without the interposition of a transformer between the tube system and the power supply system and 75 without the necessity of employing an independent rectifying tube.

The tube construction of my invention includes separate sets of grid and plate electrodes in which are interposed individual cathodes with a relatively high resistance connected between the cathodes. The resistance of the cathode is so selected that the 80 usual 110 volt 60 cycle supply can be connected directly across the cathode. The electron emitting portions of the cathode cooperating with the separated sets of grid and plate electrodes are externally connected 85 in a control system in such manner that the plate electrodes in cooperation with each of the cathodes provide means for double wave rectification of the power supply for 90 impressing across the output circuit of the 95 tube direct current for the operation of any desired form of responsive device in the output circuit.

Referring to the drawings in more detail, reference character 1 designates an evacuated vessel in which separate sets of grid and plate electrodes are arranged. I have 100 illustrated independent plate electrodes 2

and 3 in which spiral grid electrodes 4 and 5 are concentrically arranged. The plate electrodes are connected together as represented at 6; the grid electrodes are connected together as represented at 7. The cathode 8 is divided into three parts, that is, a central portion 9 consisting of a resistance, and intermediate portions 10 and 12 comprising electron emitting elements. The resistance wire forming the cathode may be swaged to shape leaving substantially large supporting end portions 14 and 15, relatively small electron emitting portions 10 and 12, and central portion 9. Electron emitting portions 10 and 12 may have electron emitting coatings 16 and 17 thereover which become heated to an electron emitting temperature upon connection of the source of alternating current supply across the leads 18 and 19 which connect with portions 14 and 15 of the cathode structure.

In Fig. 1, I have illustrated diagrammatically the external connections for the electron tube system. The signaling energy to be amplified is passed through primary winding 20 of transformer 21, which winding is coupled with secondary winding 22. In the case of a detector, a grid leak and grid condenser are connected between winding 22 and grid electrodes 4 and 5 in lead 23. In an amplification circuit, the grid leak and grid condenser are omitted. Directly across the alternating current supply circuit and leads 18 and 19 I provide a potentiometer 24 having a mid-tap 25 in which the opposite end of winding 22 is connected and to which the end of the output circuit containing lead 26 is connected. A responsive device 27 is interposed in the output circuit between the common connection 6 bridged between plates 2 and 3 and mid-tap 25 on potentiometer 24.

Where the tubes are employed in cascade amplification the primary winding 28 of transformer 29 is interposed in the output circuit of tube 1 and secondary winding 30 thereof connected at one end with mid-tap 25 of potentiometer 24 and at the other end with grids 4^a and 5^a of the second tube 1^a. The main terminals of the filament 8^a of tube 1^a are connected to the power supply lines 31 and 32 through leads 18^a and 19^a but in a reverse manner to that in which filament 8 is connected through leads 18 and 19 with the power supply system. The output circuit of tube 1^a includes primary winding 33 of transformer 34 coupled with secondary winding 35 to any desired control circuit.

The resistance of each of the cathodes is arranged so that the usual 110 volt lighting circuit power supply may be impressed directly thereacross. The length and composition of the cathode is such that while the two intermediate portions 10 and 12 become

incandescent and emit electrons, central portion 9 remains below the electron emitting temperature. The alternating current power supply is impressed upon the tube in such manner that when one end of the filament 70 is positive then the opposite end is negative, and vice versa. The two plate electrodes 2 and 3 and the two grid electrodes 4 and 5 are connected in parallel. When one end of the filament along lead 18 is negative the intermediate tap 25 of the potentiometer 24 is positive to an extent of fifty per cent of the applied voltage across the filament. At this time plate electrode 2 is positive with respect to its filament 10, and provided the 80 grid electrode 4 is of the proper polarity an electron stream will flow from filament 10 to plate 2 and current supply for the output circuit will pass through telephones 27 from plate electrode 2 across the electron stream 85 to filament electrode 10. In a similar manner the sets of electrodes 12, 5 and 3 cooperate in rectifying the other half of the power supply cycle.

It will be observed that the circuit arrangement which I have developed does not require the use of a transformer between the power supply system and the electron tube system. The middle tap 25 on the potentiometer 24 may be eliminated by means of an additional terminal 36 brought out from a mid point of the cathode portion 9. The tap connection 36 connects to the middle electrical point of the cathode. This electrical center is the mid resistance point as 100 between the mean potential point *a* of the electron emitting portion 10 and the point *c* of the other electron emitting portion. The tap 36 is taken off at a point *b* in the portion 9 of the cathode in such manner that 105 the resistance *x* between *ab* and *bc* is equal when the cathode is heated. The electron tube may be operated on any source of A. C. supply, that is any voltage or frequency. The tube construction comprises the functions of A. C. rectification for the plate circuit, and detection and amplification of signaling energy.

In the operation of the electron tube system the tubes operate as double wave rectifiers for supplying uni-direction current to the output circuits thereof at the same time that the tubes are functioning as three electrode devices in the amplification or detection of signaling currents. It will be understood that various constructions of cathodes may be provided and that the form in which I have shown the cathode is merely illustrative of the principle of my invention, and that various modifications may be made in the construction of the device without departing from the spirit of my invention. It will also be understood that various forms of hum-preventing circuits may be provided in combination with the tube system 130

of my invention in order to avoid excessive alternating current hum in the electron tube circuits.

I do not intend my invention to be limited to the particular embodiment shown, but propose that various constructions may be employed within the scope of the appended claims.

What I claim and desire to secure by Letters Patent of the United States is as follows:

1. An amplification system comprising in combination a plurality of electron tubes, each of said electron tubes having sets of grid and plate electrodes, a common cathode in each of said tubes for said sets of grid and plate electrodes, a source of alternating current, a line circuit connected with said source, connections between opposite sides 20 of said line circuit and said cathodes, and input and output circuits arranged between the grid and plate electrodes of each of said tubes with the output circuit of one of said tubes coupled with the input circuit of the 25 next adjacent tube, the next adjacent tube being coupled to the preceding tube in reverse order.

2. An amplification system comprising in combination a plurality of electron tubes, 30 each of said electron tubes having sets of grid and plate electrodes, a common cathode in each of said tubes for said sets of grid and plate electrodes, a source of alternating current, a line circuit connected with said source, connections between opposite sides 35 of said line circuit and said cathodes, each of said cathodes having electron emitting portions adjacent said sets of grid and plate electrodes, and means for balancing the drop 40 across said cathodes substantially equal to the potential of said source, a potentiometer connected across said line circuit, an input circuit for each of said tubes between the grid electrodes thereof, and a mid-point of 45 said potentiometer, an output circuit for each of said tubes between said plate elec-

trodes and a mid-point of said potentiometer, and means coupling the output circuit of one of said tubes to the input circuit of the next adjacent tube, the cathode of the 50 next adjacent tube being connected in reverse order to said line circuit.

3. An amplifying system comprising in combination a source of alternating current, a line system connected with said source, a 55 plurality of electron tubes each including sets of grid and plate electrodes, a cathode common to each of said sets of grid and plate electrodes, said cathode having a resistance value for securing a potential drop 60 thereacross substantially equal to the potential of said source, said electron tubes having input and output circuits interconnecting said grid and plate electrodes, with the next adjacent tube connecting with said line 65 system in reverse order with respect to said preceding tube.

4. An electron tube system comprising in combination a source of alternating current, an evacuated vessel, sets of grid and plate 70 electrodes contained within said vessel, a common cathode, having separate electron emitting portions adjacent each of said sets of grid and plate electrodes, and a resistance between said electron emitting portions for 75 obtaining a potential drop across the terminals of said cathode substantially equal to the potential of said source, an input circuit including said grid electrodes, an output circuit including said plate electrodes, a 80 potentiometer connected across said source, and said input and output circuits terminating at a mid-point on said potentiometer, connections between said source and opposite terminals of said cathode, whereby said 85 plate electrodes cooperate with said cathode for double phase rectification of alternating current obtained from said source for supplying uni-directional current to said output circuit. 90

In testimony whereof I affix my signature.

CLINTON W. HOUGH.
